US00D850452S

(12) **United States Design Patent** (10) **Patent No.:** **US D850,452 S**
(45) **Date of Patent:** **** Jun. 4, 2019**

(54) **COVER**

- (71) Applicant: **Apple Inc.**, Cupertino, CA (US)
- (72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans** **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

- (73) Assignee: **Apple Inc.**, Cupertino, CA (US)

- (**) Term: **15 Years**

- (21) Appl. No.: **29/624,131**

- (22) Filed: **Oct. 30, 2017**

Related U.S. Application Data

- (63) Continuation of application No. 29/598,355, filed on Mar. 24, 2017, now Pat. No. Des. 801,343, which is (Continued)

- (51) **LOC (11) Cl.** **14-02**

- (52) **U.S. Cl.**

- USPC **D14/440**

- (58) **Field of Classification Search**

- USPC **D14/356, 432, 439, 440**

Primary Examiner — Leanne Was-Englehart

(74) *Attorney, Agent, or Firm* — Sterne, Kessler, Goldstein & Fox P.L.L.C.

(57) **CLAIM**

The ornamental design for a cover, as shown and described.

DESCRIPTION

FIG. 1 is a bottom front perspective view of a cover showing the claimed design;

FIG. 2 is a top rear perspective view thereof;

FIG. 3 is a top front perspective view thereof;

FIG. 4 is a bottom rear perspective view thereof;

FIG. 5 is a front view thereof;

FIG. 6 is a rear view thereof;

FIG. 7 is a left side view thereof;

FIG. 8 is a right side view thereof;

FIG. 9 is a bottom view thereof; and,

FIG. 10 is a top view thereof.

The broken lines in the figures show portions of the cover that form no part of the claimed design.

1 Claim, 8 Drawing Sheets

Related U.S. Application Data

a continuation of application No. 29/541,555, filed on Oct. 5, 2015, now Pat. No. Des. 784,995, which is a continuation of application No. 29/492,447, filed on May 30, 2014, now Pat. No. Des. 740,292, which is a continuation of application No. 29/431,559, filed on Sep. 7, 2012, now Pat. No. Des. 706,270.

(58) Field of Classification Search

CPC A45C 2011/003; G06F 1/1628; G06F 2200/1633

See application file for complete search history.
